AIR CONDITIONING

Dion Kanouse Dean, Rahway, N. J., assignor to
 Foster Wheeler Corporation, New York, N. Y.,
 a corporation of New York

Application October 29, 1931, Serial No. 571,872

19 Claims. (Cl. 257—8)

My invention relates to air conditioning.

The process of conditioning air comprises treating the air so that it will have a desired moisture content and also a desired temperature. 5 It is usually necessary to reduce the amount of moisture normally in the air, and in order to do this the temperature of the air is first reduced below the point finally desired so that the excess moisture will be condensed. It is then necessary 10 to raise the temperature of the air to the desired point.

The major object of my invention is to provide an efficient unitary system for, first, cooling water to be used for cooling the air and, second, for 15 heating the air in its path of flow to the place of utilization. Another object of my invention is to conserve energy by utilizing heat initially removed from the air to subsequently heat the air, as above stated, in its path of flow to the place 20 of utilization.

In accordance with the preferred form of the invention, I withdraw spray water from the path of flow of the air, cause a partial vaporization thereof by a reduction in pressure in order to cool the remaining water and return the cooled 25 water to the sprays. The heat removed by the vaporization is returned to the air to heat the latter to the temperature finally desired.

Further objects and advantages of my invention 30 will be apparent from the following description considered in connection with the accompanying drawings which form a part of this specification, and on which:

Fig. 1 is a more or less diagrammatic view, 35 chiefly in cross-section, of one embodiment of my invention;

Fig. 2 is a more or less diagrammatic view of a 40 portion of a somewhat modified embodiment; and

Fig. 3 is a more or less diagrammatic view, 45 partly in cross-section of another embodiment of my invention and including automatic control devices.

Referring more particularly to Fig. 1, reference 50 character 10 designates an air conditioning chamber having an air inlet 11 and an air outlet 12. Air to be treated is supplied from any suitable source to inlet 11 by means of a fan 13. The conditioned air is led from the outlet 12 through a conduit 14 to a point of utilization, represented by a room 15.

Within air conditioning chamber 10 and adjacent to the inlet 11 are water sprays 16. Sprays 16 may consist of a series of pipes provided with small openings arranged to direct a spray of water 55 toward the incoming air. The lower part of

chamber 10 comprises a sump 17, which collects the water issuing from the sprays. This water passes through a conduit 18 provided with a valve 19 to the upper part of a flash chamber 20.

The water issuing from the end of conduit 18 within chamber 20 is broken up into more or less small drops by means of a deflector 21. Within chamber 20 there is maintained a partial vacuum by means of a thermo-compressor 22. Steam under pressure is supplied to a series of nozzles 23 10 in the thermo-compressor through a conduit 24. Water is removed from the lower part of flash chamber 20 through a conduit 25 by means of a pump 26 and is forced through a conduit 27 provided with valve 28 to the sprays 16. A by-pass 15 conduit 90 provided with a valve 91 connects conduits 18 and 27.

The discharge 29 of thermo-compressor 22 is connected to the lower part of a condenser 30. A steam jet air pump 31, which is similar to a 20 thermo-compressor 22, serves to maintain a partial vacuum within condenser 30. Cooling water is supplied to the condenser through a conduit 32, the discharge end of which is provided with a spray nozzle 33. Condensate and cooling wa- 25 ter are removed from the lower end of condenser 30 through a conduit 34 by means of a pump 35. The water discharged from pump 35 passes through a conduit 36 provided with a valve 44 to a radiator 37 located within air con- 30 ditioning chamber 10 adjacent to the outlet 12 thereof. A conduit 38 connects radiator 37 with a cooling tower or the like 39. A pump 40 sup-plies water from the cooling tower to conduit 32.

A conduit 41, provided with a valve 42, is ar- 35 ranged as a by-pass around radiator 37. A series of inclined members 45 are located within air conditioning chamber 10 between the sprays 16 and radiator 37. These inclined members serve as spray eliminators. Make-up water is 40 supplied to sump 17 through a conduit 46 provid-ed with a valve 47.

The operation of this apparatus is substantial- 45 ly as follows:

Water is removed from sump 17 through con- 45duit 18 and flows into flash chamber 20 due to the high vacuum maintained therein. The water, broken up into small drops by deflector 21 in chamber 20, is subjected to the low pressure exist-ing therein with the result that a small portion 50 of the water is caused to evaporate. Heat is re-quired for this evaporation, and this heat is taken from the water which remains unevaporated. In this way the temperature of the water is reduced, and the water removed from chamber 20 through 55

conduit 25 by pump 26 and supplied through conduit 27 to the sprays 16 is cold.

This cold water is sprayed into the air to be conditioned, and cools the air. The air is cooled sufficiently to cause the condensation of water vapor originally in the air. This condensate and the water emitted from the sprays are removed from the air by the spray eliminators 45. The air leaving the spray eliminators is considerably below the temperature finally desired and, at this low temperature, its relative humidity is approximately 100 per cent. This air is then passed in contact with radiator 37, which is supplied with hot water, as will be subsequently explained, and the air is heated to the finally desired temperature. This temperature may be controlled by regulating valves 42 and 44 so as to by-pass more or less of the hot water through conduit 41. The relative humidity of the air is lowered to the desired point due to this heating, and the air, conditioned both as to moisture content and temperature, is supplied through conduit 14 to the point of utilization 15.

The moisture content of the air may be controlled by regulating the temperature to which the air is initially cooled. If the air supplied to room 15 is too dry the temperature to which it is initially reduced should be higher. To obtain this higher temperature valve 28 may be more or less closed and valve 91 opened. A portion of the cold water from flash chamber 20 will then be recirculated through by-pass 90 and consequently less cold water will be supplied to the sprays 16.

The low pressure in flash chamber 20 is maintained by the thermo-compressor 22. Steam issues from the nozzles 23 at a high velocity and serves by ejector action to draw air and water vapor from the flash chamber. The water vapor, comprising the steam from the nozzles and that removed from chamber 20, and the air are introduced into condenser 30. Here it meets cold water supplied through spray nozzle 33, and the water vapor is condensed, thereby heating the cooling water supplied to the condenser. Steam jet jump 31 removes air and any other non-condensable gases from the condenser and thereby maintains a low pressure in the condenser.

The condensate and heated cooling water are removed from condenser 30 through conduit 34 and are forced by pump 35 through conduit 36 to radiator 37. In radiator 37 the hot water heats the air as previously described. The degree of heating may be controlled by manipulating valves 42 and 44 so as to by-pass more or less of the hot water around the radiator. The hot water is finally led through conduit 38 to a cooling tower or the like 39, where it is cooled and may be supplied by pump 40 to condenser 30.

Due to the evaporation of a small percentage of the water in flash chamber 20, it is necessary to supply a small amount of make-up water to the circulating system including the sprays and the flash chamber. This make-up water is supplied in part by the moisture condensed from the air, and if this is not sufficient, additional make-up water may be admitted through conduit 46.

Fig. 2 is a cross-sectional view of the outlet 70 end of air conditioning chamber 10 showing a modified form of construction. Chamber 10, adjacent to outlet 12 thereof, is divided into two compartments 50 and 51. Admission of air to compartments 50 and 51 is controlled by dampers 75 52 and 53, respectively. These dampers may

be mechanically connected by means of cranks 54 and 55 and a rod 56 to a single operating handle 57 in such a way that when one damper is opened the other is closed. Handle 57 preferably is automatically operated by means of a temperature responsive device comprising a thermostatic bulb 58 located in the path of air flow, as in outlet 12. A conduit 59 connects bulb 58 with a cylinder 60 in which is a piston connected to one end of rod 61. The other end of rod 61 is pivotally connected to handle 57. Radiator 37 is located in compartment 50.

In the operation of this modification the air is cooled to a temperature below that finally desired in order to condense excess moisture in 15 the same manner as described in connection with Fig. 1. The air is then passed through spray eliminators 45, but instead of all of the air being heated to the desired temperature, a portion of the air is passed through chamber 50 where it 20 is heated to a temperature above that finally desired. The remainder of the air is passed through chamber 51, where it receives no further treatment and is subsequently mixed with the heated air from chamber 50. The distribution of the air 25 between chambers 50 and 51 is so regulated by means of dampers 52 and 53 that the mixture has the temperature finally desired.

This regulation may be automatic, as is shown. Bulb 58 contains a fluid which expands upon a 30 rise in temperature and conduit 59 and cylinder 60 also contain fluid. Hence, if the temperature of the air passing through outlet 12 rises above a predetermined value, the fluid in bulb 58 expands and forces the piston upwardly in cylinder 35 60, thereby causing rotation of handle 57 in a clockwise direction. This causes rod 56 to move upwardly, thus closing damper 52 and opening damper 53. Consequently, less air passes through chamber 50 in contact with radiator 37 and more 40 air passes through chamber 51 and the temperature of the resulting mixture is lowered. If the air becomes too cold, the reverse action occurs and more air is passed through chamber 50 and less through chamber 51.

In Fig. 3 there is illustrated a somewhat modified embodiment of my invention. Reference character 10 designates the air conditioning chamber provided with an inlet 11 and an outlet 12. Centrifugal fan 13 is connected to discharge 50 air into the inlet 11 while conduit 14 connects the outlet 12 with a room or the like 15.

Within chamber 10 adjacent to the inlet 11 thereof is positioned a series of sprays 16. The lower part of chamber 10 comprises a sump 17 55 divided into liquid receivers 110 and 111 by partition 112 which may have an aperture 113 near the bottom thereof. The liquid ejected from the sprays is collected in receiver 111. A conduit 65 leads from the lower part of receiver 110 to 60 a pump 66, the discharge of which is connected by means of a conduit 67 with the sprays 16. To the lower part of receiver 111 there is connected conduit 18 which leads to the upper part of flash chamber 20. Flash chamber 20 is connected to 65 the inlet of the thermo compressor 22 which is supplied with steam through a conduit 24. Thermo compressor 22 discharges into a condenser 30 which is supplied with cooling water through a conduit 22 from a cooling tower 39. A 70 partial vacuum is maintained in condenser 30 by means of a steam jet air pump 31. Flash chamber 20, thermo compressor 22, condenser 30, steam jet vacuum pump 31 and cooling tower 39 shown in Fig. 3 are the same as previously 75

illustrated and described in detail in connection with Fig. 1, and hence it is not necessary to repeat the detailed description here.

The lower part of flash chamber 20 is connected by means of a conduit 25 with a pump 26 which discharges through a conduit 27 to receiver 110. The by-pass conduit 68 connects conduits 18 and 27. A valve 69 is interposed in conduit 18 between receiver 111 and the point of communication of by-pass 68 with conduit 18. A valve 70 is interposed in by-pass 68.

Valves 69 and 70 are automatically operable in response to the moisture content of the air in room 15. Valve 69 is provided with a valve member 71 mounted on a valve stem 72 attached to a piston 73 which is slidably positioned within a cylinder 74. A spring 75 acts upon piston 73 in such a manner as to tend to open the valve. A conduit 76 communicates with cylinder 74 and with a conduit 77. Conduit 77 is connected to any suitable source of fluid under pressure. Valve 70 is provided with a valve member 78 mounted on a valve stem 79 secured to a piston 80 which is slidably mounted within a cylinder 81. A spring 82 acts upon piston 80 in such a manner as to tend to close the valve. A conduit 83 connects cylinder 81 with conduit 77.

Within room 15 there is located a device responsive to the moisture content of the air in the room. This device is shown as comprising strips of catgut 84 secured at one end to a stationary member 85 and at the other end to a member 86 which is fastened to a pivoted arm 87. A spring 88 tends to move arm 87 so as to stretch the catgut. The open end of a conduit 89 is located in close proximity to the free end of lever 87 so as to be closed by that lever when the latter is rotated in a counter-clockwise direction. The other end of conduit 89 is connected to conduit 77.

The lower part of condenser 30 is connected by means of a conduit 34 to a pump 35 which discharges through a conduit 36. Conduit 36 is connected by means of a conduit 92 with the radiator 37 located in air conditioning chamber 10. A valve 93 is interposed in conduit 92. The other end of radiator 37 is connected by means of conduit 38 with the cooling tower 39. A conduit 41 is connected to conduits 36 and 38 so as to form a by-pass around radiator 37. A valve 94 is located in conduit 41.

Valves 93 and 94 are automatically controlled in accordance with the temperature of the air in room 15. Valve 93 is provided with a valve member 95 while valve 94 has a valve member 96. Valve members 95 and 96 are mounted on a common valve stem 97 which is provided with a pin 98. Pin 98 is engaged by a lever 99 pivoted at 100. The other end of lever 99 is pivotally connected to a rod 101 which is connected to a piston which operates in a cylinder 102. The cylinder 102 is connected by means of a conduit 103 with a thermostatic bulb 104 located in room 15. Bulb 104 contains a fluid which expands upon a rise in temperature and thus exerts a pressure which is transmitted through conduit 103 to the piston in cylinder 102, moving the piston and the rod 101 to the left, as viewed in Fig. 3.

This modification of my invention operates substantially as follows:

Thermo compressor 22 maintains a partial vacuum within flash chamber 20, as was explained in connection with Fig. 1, whereby water from receiver 111 of sump 17 will flow through conduit 18 to the upper part of the flash chamber. In the flash chamber a portion of this water

is evaporated, whereby the remaining water is cooled and leaves the flash chamber through conduit 25 and is forced by pump 26 through a conduit 27 back to receiver 110 of sump 17. Water is withdrawn from receiver 110 through conduit 65 and forced by pump 66 through conduit 67 to the sprays 16. If valve 69 is partially closed and valve 70 partially opened, as will be explained subsequently, pump 66 will remove water from receiver 110 faster than water is supplied to this receiver through conduit 27 and water from the sprays will flow into receiver 111 faster than it is removed through conduit 18. In this event, water will flow from receiver 111 through aperture 113 in partition 112, or over the top of the 15 partition, into receiver 110. In other words, a portion of the water is recirculated through the sprays without having passed through the flash chamber. The water ejected from the sprays comes in intimate contact with the air to be 20 treated which is forced into chamber 10 by means of fan 13. The water, which is cold, cools the air and thereby causes the precipitation of a portion of the moisture normally present in the air.

The air passes through spray eliminators 45 at 25 a temperature below that finally desired and then comes in contact with radiator 37, which is supplied with hot water, and the air is thereby heated to the desired temperature. Hot water is supplied to radiator 37 from condenser 30 in the 30 same manner as described in connection with Fig. 1.

In the event that the air supplied to room 15 contains more moisture than is desired, catgut 84 will shrink due to the presence of the excess 35 moisture and will cause lever 87 to move away from the open end of conduit 89. Thus, the fluid under pressure in conduit 89 is allowed to escape with the result that the pressure in conduits 77, 76 and 83 and in cylinders 74 and 81 falls. This 40 allows springs 75 and 82 to move pistons 73 and 80, respectively. The movement of piston 73 causes valve 69 to be opened a greater amount while the movement of piston 80 causes valve 70 to be closed a greater amount. The result is that 45 more water is withdrawn from receiver 111 and passed through flash chamber 20 and returned to receiver 110 than was formerly the case. Hence, less water passes through aperture 113 and the water present in receiver 110 is colder 50 and therefore the water supplied to sprays 16 is colder. This causes the temperature of the air to be reduced to a lower degree which in turn causes more of the moisture carried by the air to be condensed. Hence, the air supplied to 55 room 15 becomes drier. On the other hand, if the air supplied to the room becomes too dry catgut 84 stretches allowing spring 88 to move lever 87 so as to close the open end of conduit 89. This permits pressure to be built up within cylinders 74 and 81. Pistons 73 and 80 are thereby moved against the force of springs 75 and 82, respectively. This causes valve 69 to be closed to some extent while valve 70 is opened. The result is that a greater portion of the water dis- 60 charged from flash chamber 20 is recirculated through by-pass conduit 68 back to the flash chamber and a less amount is supplied to receiver 110. Likewise, a less amount is withdrawn from receiver 111 through conduit 18. Hence, as the 70 flow through the sprays is constant, more water passes through aperture 113 and the temperature of the water in receiver 110 becomes higher and the air to be treated is not reduced to such a low temperature. Less water is therefore con- 75

densed from the air and the air supplied to room 15 has a higher moisture content. It will thus be seen that the initial cooling of the air is controlled directly in accordance with the moisture content of the conditioned air. That is to say, the greater the moisture content, the greater is the degree of cooling and vice versa.

The temperature of the air supplied to room 15 is controlled by means of valves 93 and 94. If 10 the air becomes too warm the fluid within thermostatic bulb 104 expands and forces the piston within cylinder 102 to the left. This causes lever 99 to pivot in a clockwise direction and to thus move valve stem 91 to the right. The result of this movement of the valve stem is to open valve 94 and to close valve 95. This results in more of the hot water supplied through conduit 36 being by-passed around radiator 37 and hence the air passing in contact with the radiator is not heated to such a high temperature. If the air becomes too cold the reverse operations take place and valve 95 is open and valve 94 is closed. Thus, more of the hot water is passed through radiator 37 and less of it is by-passed.

25 It will be seen that the heat imparted to the air after its initial cooling is in part heat which has been removed from the air during the process of initial cooling. This heat is raised to a higher temperature level and then returned to the air.

30 Hence, the system is very economical.

In the event that the air conditioning apparatus is to be used for heating the air in the winter time, it may become necessary to supply additional heat from outside the system. In this 35 event, such steam may be supplied directly to radiator 37 or an additional radiator may be provided or other means for heating the air, such as electric or gas heaters may be used.

40 The temperature and humidity controls may be placed anywhere in the air circuit. Thus, they may be located in the room, as shown in Fig. 3, or they might be located in conduit 14, as is the temperature control shown in Fig. 2, or they might be located in an air outlet from the 45 room 15.

There is illustrated one method of cooling the air by the water, that of spraying the water into the air. However, if desirable, the cooling water may be circulated through conduits preferably 50 provided with extended external surfaces, in contact with the air.

While I have disclosed several embodiments 55 of my invention, it is to be understood that these particular embodiments have been selected for purposes of illustration only and that my invention is not to be limited thereby, but is to be determined by the scope of the following claims.

What I claim is:

1. An apparatus for conditioning air comprising means for spraying water into the air to cool said air, means for evaporating a portion of the water to cool the remaining water, means for conveying condensing the water vapor, means for conveying heat from the condensate to said air out of 65 contact with the condensate, and means for supplying said air to a point of utilization.

2. An apparatus for conditioning air comprising means for spraying water into the air to cool said air, a flash chamber, means for conveying 70 said water to said flash chamber, means for maintaining a partial vacuum in said flash chamber, means for conveying water from said flash chamber to the spraying means, and automatic means responsive to the moisture content of air 75 which has been conditioned for controlling the

temperature of the water supplied to said spraying means.

3. An apparatus for conditioning air comprising an air conditioning chamber having an air inlet and an air outlet, means for passing air through said chamber, means for bringing said air into heat exchange relationship with a cooling fluid in said chamber, a radiator adjacent said air outlet, means for evaporating a portion of said cooling fluid to cool the remainder, 10 means for returning the cooled fluid into heat exchange relationship with air passing through said chamber, means for condensing the evaporated cooling fluid, and means for passing the condensed fluid through said radiator. 15

4. An apparatus for conditioning air comprising an air conditioning chamber having an air inlet and an air outlet, means for passing air through said chamber, means for spraying water into the air in said chamber adjacent said air inlet, a radiator adjacent said air outlet, means for vaporizing a portion of the water from said spraying means, means for condensing the evaporated water and said steam, and means for passing said condensate through said radiator. 25

5. An apparatus for conditioning air comprising an air conditioning chamber having an air inlet and an air outlet, means for passing air through said chamber, means for bringing water into heat exchange relationship with the air in 30 said chamber, a radiator adjacent said air outlet, means for evaporating a portion of said water, a condenser, means for conducting the evaporated water to said condenser, and means for passing water containing heat of condensation from said 35 condenser through said radiator.

6. An apparatus for conditioning air comprising an air conditioning chamber having an air inlet and an air outlet, means for passing air through said chamber, means for spraying water 40 into the air in said chamber adjacent said air inlet, a radiator adjacent said air outlet, means for evaporating a portion of said water to cool the remainder, means for returning the cooled water to the spraying means, means for condensing the evaporated water, means for passing water containing the heat of condensation through said radiator, and means for by-passing the last mentioned water around said radiator. 45

7. An apparatus for conditioning air comprising 50 an air conditioning chamber, the lower part of said chamber forming two liquid receivers, heat exchange means located in said chamber, means for conveying liquid from one receiver to said heat exchange means, means for conveying 55 liquid from said heat exchange means to the other receiver, means for evaporating a portion of the liquid from said other receiver to cool the remaining liquid, means for conveying cooled liquid to said one receiver, and means establishing liquid communication directly between said receivers.

8. An apparatus for conditioning air comprising 60 an air conditioning chamber, the lower part of said chamber forming two liquid receivers, 65 heat exchange means located in said chamber, means for conveying liquid from one receiver to said heat exchange means, means for conveying liquid from said heat exchange means to the other receiver, means for evaporating a portion 70 of the liquid from said other receiver to cool the remaining liquid, automatic means responsive to the moisture content of the conditioned air for controlling the quantity of liquid conveyed from said other receiver to said evaporating means, 75

means for conveying liquid from said evaporating means to said one receiver, and means establishing liquid communication directly between said receivers.

5. 9. An apparatus for conditioning air comprising an air conditioning chamber, the lower part of said chamber forming two liquid receivers, heat exchange means located in said chamber, means for conveying liquid from one receiver to said heat exchange means, means for conveying liquid from said heat exchange means to the other receiver, means for evaporating a portion of the liquid from said other receiver to cool the remaining liquid, means for conveying liquid from said evaporating means to said one receiver, automatic means responsive to the moisture content of the conditioned air for recirculating liquid discharged from said evaporating means back to said evaporating means, and means establishing liquid communication directly between said receivers.

10. 10. An apparatus for conditioning air comprising an air conditioning chamber, the lower part of said chamber forming two liquid receivers, spraying means located in said chamber, means for conveying liquid from one receiver to said spraying means, means for conveying liquid from said spraying means to the other receiver, evaporating means, a conduit for conveying liquid from said other receiver to said evaporating means, a first valve in said conduit, a conduit for conveying liquid from said evaporating means to said one receiver, a by-pass conduit connecting said conduits, a second valve in said by-pass conduit, automatic means responsive to variations in the moisture content of the conditioned air for opening said first valve and closing said second valve upon an increase in the moisture content, and means establishing liquid communication directly between said receivers.

45. 11. The method of conditioning air which comprises bringing cooling water into heat exchange relationship with the air to remove heat from the air and thereby reduce the temperature thereof, evaporating a portion of the water to remove heat from the remaining water, conveying the heat so removed to the air in order to raise the temperature thereof, and conveying the heated air to the point of use.

50. 12. Apparatus for conditioning air comprising means for bringing cooling water into heat exchange relationship with the air to cool said air, means for evaporating a portion of the water to cool the remaining water, means for condensing the water vapor, means for conveying heat from the condensate to said air out of contact with the condensate, and means for supplying said air to a point of utilization.

60. 13. The method of conditioning air which comprises bringing cooling water into heat exchange relationship with the air to remove heat from the air and thereby reduce the temperature thereof, evaporating a portion of the water to remove heat from the remaining water, conveying the heat to the air at a higher temperature than that at which it was removed from the air, in order to raise the temperature of the air and conveying the heated air to the point of use.

70. 14. An apparatus for conditioning air comprising an air conditioning chamber having an

air inlet and an air outlet, means for passing air through said chamber, means for bringing said air into heat exchange relationship with a cooling fluid in said chamber, means for evaporating a portion of said cooling fluid to cool the remainder, means for returning the cooled fluid into heat exchange relationship with air passing through said chamber, means for condensing the evaporated cooling fluid, and means for passing the condensed fluid into heat exchange relationship with the cooled air.

5. 15. An apparatus for conditioning air comprising an air conditioning chamber having an air inlet and an air outlet, means for passing air through said chamber, means for spraying water into the air in said chamber adjacent said air inlet, means for vaporizing a portion of the water from said spraying means, means for condensing the evaporated water and means for passing said condensate into heat exchange relationship with the air subsequent to its contact with the spray water.

15. 16. An apparatus for conditioning air comprising an air conditioning chamber having an air inlet and an air outlet, means for passing air through said chamber, means for bringing a cooling fluid into heat exchange relationship with the air in the chamber to cool the air, means for evaporating a portion of said cooling fluid to cool the remainder, means for returning the cooled fluid into heat exchange relationship with the air, means for condensing the evaporated fluid, means for bringing the condensate into heat exchange relationship with the cooled air to heat the air, and means for by-passing the condensate out of heat exchange relationship with the cooled air.

20. 17. The method of conditioning air which comprises spraying cold water into the air to remove heat from the air and thereby reduce the temperature thereof, precipitating moisture from the air due to the reduction in temperature, removing heat from the water by evaporating a portion of the water, conveying the heat to the air in order to raise the temperature of the air, and controlling the removal of heat from the air in response to the moisture content of air which has been conditioned.

25. 18. The method of conditioning air which comprises spraying cold water into the air to remove heat from the air and thereby reduce the temperature thereof, precipitating moisture from the air due to the reduction in temperature, removing heat from the water by evaporating a portion of the water, conveying the heat to the air in order to raise the temperature of the air, and controlling the heating of the air in response to the temperature of air which has been conditioned.

30. 19. Apparatus for conditioning air comprising means for bringing a cooling fluid into heat exchange relationship with the air to cool the air, means for evaporating a portion of the cooling fluid to cool the remaining fluid, means for circulating the fluid from the first mentioned means to the second mentioned means and return, and automatic means responsive to the moisture content of the air which has been conditioned for controlling the temperature of the cooling fluid supplied to the first mentioned means.
